UNITED STATES PATENT OFFICE.

CALEB DAVIES, JR., OF POLAND, OHIO.

OPEN-HEARTH FURNACE.

Application filed April 6, 1922. Serial No. 550,079.

To all whom it may concern:

Be it known that I, CALEB DAVIES, Jr., a citizen of the United States, and a resident of Poland, county of Mahoning, and State 5 of Ohio, have invented a new and useful Improvement in Open-Hearth Furnaces, of which the following is a specification, the principle of the invention being herein explained and the best mode in which I have 10 contemplated applying that principle, so as to distinguish it from other inventions.

The modern open hearth steel furnace is a rectangular box-like structure enclosing a shallow hearth upon which the material 15 entering into the manufacture of steel is melted and refined, the necessary heat for the operation being supplied by a flame playing over such hearth. This flame is usually produced by the combustion of 20 gaseous fuel, which, together with the air necessary to support combustion, is supplied through large ducts located at either end of the furnace. The openings at the opposite ends of the furnace are identical in 25 size and shape, and are so arranged that the process may be reversed, the gas with the usual amount of air for combustion being alternately supplied, first in one end, then the other, and the products of combustion 30 being drawn out at the opposite end.

The great majority of modern open hearth furnaces are fired with producer gas and considerable difficulty is experienced in adapting the same for use with 35 richer gases, such as coke oven gas and the like. The object of the present invention accordingly is to provide an arrangement for introducing coke oven or other gas into an open hearth furnace in such a way that 40 even with an unusually small excess of air practically no unburned gas can reach the roof, and at the same time no blowers and no stationary or removable constructions in 45 passages for air or products of combustion will be required.

To the accomplishment of the foregoing and related ends, said invention, then, consists of the means hereinafter fully describe and particularly pointed out in the 50 claims; the annexed drawings and the following description setting forth in detail certain mechanism embodying the invention, such disclosed means constituting, however, but several of the various mechanical

forms in which the principle of the invention may be used.

In said annexed drawings:—

Fig. 1 is a central longitudinal section through one end of a typical open hearth furnace wherein the construction has been 60 modified for introduction of the gaseous fuel in accordance with my present improvement; Fig. 2 is a horizontal section of the same, the plane of the section being indicated by the line 2—2, Fig. 1; Fig. 3 is a 65 vertical section of a detail taken on the same plane as that of Fig. 1, but on a larger scale; Fig. 4 is a view similar to Fig. 1, but illustrating a modification in construction; Fig. 5 is a vertical transverse section 70 of such modified construction, the plane of the section being indicated by the line 5—5, Fig. 4; Fig. 6 is a horizontal plan view more or less diagrammatic in character of a furnace constructed in accordance with either 75 of the foregoing designs and embodying an additional feature of improvement; Fig. 7 is a vertical transverse section of such last-mentioned construction, the plane of the section being indicated by the line 7—7, Fig. 80 80; and Fig. 8 is a view similar to Fig. 7, but illustrating a modified form of such additional detail of construction.

In the construction illustrated in Figs. 1, 2 and 3 of the drawings I utilize the standard type of producer-gas fired furnace, except that the gas ports and all partitions between producer-gas and air passages are removed down to the upper part of the air and gas slag pockets 1 and 2. An open 85 vertical passage 3 is accordingly left, the upper end of which communicates through an unobstructed port opening 4 with the furnace chamber 5. As previously explained the two ends of the furnace are 90 substantially identical in construction, only one such end accordingly being illustrated in Figs. 1 and 2. Gas regenerators are used 95 for heating the air as in the aforesaid standard construction, and the air steam 100 will enter the furnace proper with nearly uniform velocity in all parts of the passage 3, and with all parts approximately parallel to the front and back walls of the furnace as such steam is thence discharged through 105 port opening 4 into the furnace chamber 5 proper.

Extending across the furnace from front

to back, underneath this air stream at each end of the hearth, is a removable water-cooled brick covered gas pipe 6 with a slot or equivalent line of holes at one side for a gas outlet. The detail construction of this pipe will be readily understood from Fig. 3, where it will be seen that the concentric jacket 7^a completely encloses said pipe, except for such gas outlet opening 7. The 10 brick 8, in which such water-cooled pipe is thus embedded, forms the port sill for the opening 4, through which the heated air is supplied as aforesaid to the furnace chamber, and a slot 9, formed in such brick in 15 alignment with the slot 7 in the pipe, permits the escape of gas from the latter and further assists in directing the gas stream in an approximately horizontal direction underneath the stream of air. It may be found 20 desirable to have such discharge slot 7, and the slot 9 thus aligned therewith, tilted slightly downward, but the important thing is to have each part of the gas stream at the burner outlet as nearly proportional as possible to that part of the air stream which lies 25 directly above it. Of course, the simplest ideal condition for this is such, that if gas and air streams be considered as cut by a series of equidistant imaginary planes 30 parallel to the longitudinal axis of the furnace, each such imaginary section would have a like proportion of the total air flow, a like proportion of the total gas flow, and therefore the same ratio of air flow to gas 35 flow; and each such imaginary vertical plane would be parallel to the air and gas streams. In practice, however, the air stream may well be slightly wider than the gas stream, and that portion of the air stream which is 40 near the front and back walls may be slightly slower than the rest, thus to protect these walls.

In order to compensate for lack of uniformity in the rate of flow of the air stream 45 at different points transversely of port opening 4, due to different frictional resistance encountered and other causes, the slot opening 7 may be initially designed to have a corresponding variation in width at different points transversely of the furnace. Since, however, the conditions under consideration are subject to change I prefer to 50 provide means such for example, as shown in Figs. 2 and 3 for adjustably varying the width of the slot opening at different points transversely of the pipe 6, such means in the form illustrated comprising a plurality of relatively short sections 10 of pipe rotatably fitted within said pipe 6 in end to end 55 relation, such sections having slots 11 cut therein of a width equal to or greater than that of slot 7. A suitable stem or rod (not shown), operable from one end of the pipe, is adapted to be brought into engagement 60 with said pipe sections 10, and, by partially

rotating them, cut off more or less of the slot 7 and correspondingly reduce the volume of gas escaping at this point.

Under the conditions hereinbefore described, the path of the gas is the resultant 70 of two forces, one due to the direction and linear velocity with which it leaves the burner, and the other due to the low specific gravity with respect to the air or products of combustion. The path of the gas thus turns upward, but if there is even a slight 75 excess of air, and if the above-described relative distribution of gas and air exists, no considerable portion of the gas can get to the roof without meeting its share of air, and therefore being burned. With low 80 pressure and wide gas slot in the burner pipe 6, or with upward tilt of the burner opening, the flame will appear short even with no excess air; while with a narrower 85 burner slot and higher pressure for the same gas flow, the burner being properly tilted, a much longer flame will be obtained. Of course the flame is also affected by the air 90 velocity, but with the above described arrangement, whereby the ratio of air to gas may be maintained constant, the greater the linear velocity of the air the greater will be 95 the flame length.

The utilization of my improved design of furnace is not necessarily limited to the case where a relatively rich gas, such as coke oven gas, is employed, but is also adaptable, upon making certain modifications for use 100 with producer gas. Thus, as shown in Fig. 4, the partition 15 between the air slag pocket 1 and gas slag pocket 2 may be carried upwardly and thence forwardly in a general horizontal direction into the throat 105 of the port 4, such horizontally extending portion 15^a being suitably reinforced by water-cooled pipes 15^b so as to enable same to be made of relatively light construction 110 and not take up too much space in such port opening. As a result the producer gas supplied from the gas slag pocket is discharged through a relatively wide low opening beneath the stream of air, both said gas stream and air stream extending substantially 115 across the entire width of the furnace and being properly proportioned in relative volumes to give the best results.

In order to give a longer flame and compensate for insufficient velocity at the main burner, whatever the particular type of the latter, I may place auxiliary burners in the front and back walls of the furnace or in the roof at a point approximately midway between the respective ends of the furnace. One such modified arrangement illustrating 120 the use of auxiliary burners 16 projecting through the furnace walls is shown in Figs. 6 and 7. These transversely disposed auxiliary burners are preferably located below 125 the air stream, and will use up air at differ- 130

ent rates at different distances from the side walls of the furnace. This irregular transverse distribution of air requirement of the auxiliary burners may be compensated by adjustment of gas distribution at the outlet of the end burner.

The auxiliary burners may, however, be located over the air stream or be adjustable in vertical position, as illustrated in Fig. 8, 10 where a transverse pipe 17, having downwardly directed discharge openings or a slot is shown, said pipe being of a length approximately equal to the transverse width of the furnace and being supported by vertical extensions 17^a at each end, that pass through suitable openings 18 in the furnace roof 19. The pipe 17 and its vertical extensions 17^a may be water-cooled and brick-covered. This type of burner is adapted, if 20 desired, to be raised, as indicated in dotted outline, into a position directly below the roof 19, where it will be out of the way during the charging of the furnace, and then may be lowered down close to the stock and 25 under most of the excess air. After "melting down" is completed, this burner may be submerged in the bath, giving a reducing effect.

The main object sought to be accomplished by my improved furnace construction, whatever its particular form, is to introduce the gas mostly under the air stream, with or without contact with the bath, in such a way that the total gas flow in most 30 of the vertical longitudinal elements of the furnace will be properly proportioned to the total air flow in those elements, thus giving control, not only of heat distribution, but also of oxidizing or reducing conditions. 35 It will be understood of course that the principle of operation exemplified in my improved furnace construction is not necessarily limited to an open hearth furnace of the type hereinbefore referred to, but is applicable to other similar types of furnaces; also that liquid hydrocarbon and other fuels that may be introduced in a similar manner may be substituted for the gaseous fuels referred to above.

50 Other modes of applying the principle of my invention may be employed instead of the one explained, change being made as regards the means and the steps herein disclosed, provided those stated by any one of 55 the following claims or their equivalents be employed.

I therefore particularly point out and distinctly claim as my invention:—

1. In a furnace of the character described, 60 the combination of a hearth, an air port at the end thereof extending approximately entirely across said hearth, and a fuel supply duct formed and arranged to discharge the fuel beneath the stream of air from said air port and in a direction substantially paral-

lel therewith, such fuel supply duct being of approximately the same transverse width as said air port.

2. In a furnace of the character described, the combination of a hearth, an air port at 70 the end thereof extending approximately entirely across said hearth, and a fuel supply duct constructed and arranged to discharge a thin layer of fuel beneath and in a direction substantially parallel with the 75 stream of air from said air port, such fuel supply duct being of approximately the same transverse width as said air port.

3. In a furnace of the character described, the combination of a hearth, an air port at 80 the end thereof extending approximately entirely across said hearth and formed and arranged to discharge the air thereover in a substantially horizontal direction, and a fuel supply duct formed and arranged to discharge a thin layer of fuel beneath and in a direction substantially parallel with the stream of air from said air port, such fuel supply duct being of approximately the same transverse width as said air port. 90

4. In a furnace of the character described, the combination of a hearth, an air port at the end thereof extending approximately entirely across said hearth, and a fuel supply duct constructed and arranged to discharge the fuel beneath the stream of air from said air port and in regulated amounts at different points transversely of said hearth to correspond with the air flow at such points. 95

5. In a furnace of the character described, the combination of a hearth, an air port at the end thereof extending approximately entirely across said hearth, a fuel supply duct having a transverse discharge opening disposed below said air port, and adjustable means adapted to regulate the amount of fuel discharged from said duct opening at different points therealong. 100

6. In a furnace of the character described, the combination of a hearth, an air port at 110 the end thereof extending approximately entirely across said hearth, and a transversely extending gas supply pipe embedded in the sill of said air port, said pipe and sill being formed with aligned openings whereby the gas is discharged in a thin layer beneath the stream of air from said air port. 115

7. In a furnace of the character described, the combination of a hearth, an air port at the end thereof extending approximately entirely across said hearth, and a transversely extending water-cooled gas supply pipe embedded in the sill of said air port, said pipe and sill being formed with aligned openings whereby the gas is discharged in a thin layer beneath the stream of air from said air port. 120

8. In a furnace of the character described, the combination of a hearth, an air port at the end thereof extending approximately en- 125

- 4
- tirely across said hearth, a transversely extending gas supply pipe embedded in the sill of said air port, said pipe and sill being formed with aligned openings whereby the 5 gas is discharged in a thin layer beneath the stream of air from said air port, and adjustable members in said pipe whereby the amount of fuel discharged through such openings at different points may be regulated. 10 9. In a furnace of the character described, the combination of a hearth, an air port at the end thereof extending approximately entirely across said hearth, a fuel supply duct constructed and arranged to discharge the 15 fuel beneath the stream of air from said air port, and a supplemental fuel supply duct discharging into said furnace at a point longitudinally spaced from such end. 10 10. In a furnace of the character described, 20 the combination of a hearth, an air port at the end thereof extending approximately entirely across said hearth, a fuel supply duct constructed and arranged to discharge the fuel beneath the stream of air from said 25 air port, and a supplemental fuel supply duct discharging into said furnace at a point longitudinally spaced from such end, said supplemental fuel supply duct being vertically adjustable. 30 11. In a furnace of the character described, the combination of a hearth, an air port at the end thereof extending approximately entirely across said hearth, a fuel supply duct constructed and arranged to 35 discharge the fuel beneath the stream of air from said air port, and a supplemental fuel supply duct discharging into said furnace at a point longitudinally spaced from such end, said supplemental fuel supply 40 duct extending transversely of said hearth. 12. In a furnace of the character described, the combination of a hearth, an air port at the end thereof extending approximately entirely across said hearth, a fuel 45 supply duct constructed and arranged to discharge the fuel beneath the stream of air from said air port, and a supplemental fuel supply duct discharging into said furnace at a point longitudinally spaced from such 50 end, said supplemental fuel supply duct extending transversely of said hearth and being vertically adjustable. 13. In a method of firing an open-hearth furnace, the steps which consist in introducing 55 a stream of air in an approximately horizontal direction over the hearth from one end thereof, such stream extending across the entire width of the hearth, and discharging the fuel beneath such air stream in a 60 layer of approximately equal transverse width. 14. In a method of firing an open-hearth furnace, the steps which consist in introducing a stream of air in an approximately 65 horizontal direction over the hearth from
- one end thereof, such stream extending across the entire width of the hearth, and discharging the fuel in a thin transversely extending layer beneath such air stream and in a direction approximately parallel 70 therewith. 15. In a method of firing an open-hearth furnace, the steps which consist in introducing a stream of air in an approximately 75 horizontal direction over the hearth from one end thereof, such stream extending across the entire width of the hearth, and discharging the fuel in a thin layer beneath such air stream and in regulated amounts at different transverse points to correspond 80 approximately with the volume of air introduced at such points. 16. In a method of firing an open-hearth furnace, the steps which consist in introducing a stream of air in an approximately 85 horizontal direction over the hearth from one end thereof, such stream extending across the entire width of the hearth, discharging the main supply of fuel in a thin layer beneath such air stream, and discharging a supplemental supply of fuel into said furnace at a point longitudinally spaced 90 from such end. 17. In a method of firing an open-hearth furnace, the steps which consist in introducing a stream of air in an approximately 95 horizontal direction over the hearth from one end thereof, such stream extending across the entire width of the hearth, discharging the main supply of fuel in a thin layer beneath such air stream, and discharging a supplemental supply of fuel into said furnace at a point longitudinally spaced 100 from such end and at different heights at different stages of operation. 18. In a method of firing an open-hearth furnace, the steps which consist in introducing a stream of air in an approximately 105 horizontal direction over the hearth from one end thereof, such stream extending across the entire width of the hearth, discharging the main supply of fuel in a thin layer beneath such air stream, and discharging a supplemental supply of fuel into said furnace at a point longitudinally spaced 110 from such end and at a decreasing height at successive stages of operation. 19. In a method of firing an open-hearth furnace, the steps which consist in introducing a stream of air in an approximately 115 horizontal direction over the hearth from one end thereof, such stream extending across the entire width of the hearth, discharging the main supply of fuel in a thin layer beneath such air stream, and discharging at certain stages in the operation of the furnace a supplemental supply of fuel directly into the molten bath in said furnace at a point longitudinally spaced from such end. 120 125 130

20. In a method of firing an open-hearth furnace, the steps which consist in introducing a stream of air in an approximately horizontal direction over the hearth from one end thereof, such stream extending across the entire width of the hearth, discharging the main supply of fuel in a thin layer beneath such air stream, discharging a supplemental supply of fuel into said furnace at a point longitudinally spaced ¹⁰ from such end, and adjusting the transverse distribution of fuel in the main supply to compensate for varying transverse distribution of air requirement of such supplemental fuel supply. ¹⁵

Signed by me this 10th day of April, 1922.

CALEB DAVIES, Jr.
